CONTROL APPARATUS FOR RADIO RECEIVERS

Alexander W. Plensler, Chicago, Ill., assignor to Belmont Radio Corporation, Chicago, Ill., a corporation of Illinois

Application February 27, 1939, Serial No. 258,609

11 Claims.

(Cl. 74—10)

My invention relates in general to control apparatus for radio receivers and more in particular to manually operated automatic tuners for such receivers.

In automatic tuners for radio receivers some portion of the tuners is adjustable with reference to another portion so that the apparatus as a whole may be set to predetermined signal frequency positions, and such positions varied from time to time in accordance with the desires of the operator. In many of the prior tuners rather complicated apparatus is required for the adjusting and setting operation and in many instances independent tools, such as screw drivers and the like, are employed. These structures are objectionable either from the standpoint of cost or from the fact that it is necessary to normally go to some trouble to find the adjusting tool.

An object of my invention is to provide a simplified tuner for manual operation which can be set and reset to predetermined tuning positions by the active elements of the tuner itself.

A further object of my invention is to provide a tuner which can be set and reset from the front of the apparatus without any extra tools.

A still further object of my invention is to provide a manually operated automatic tuner for a radio receiver having a plurality of control elements on a rotary shaft with each control element adapted to be set or reset to a predetermined position independently of the other control elements, and while maintaining such other control elements rigid on the rotary shaft.

One of the features of my invention is the provision of a combination selector or push-button unit and adjusting tool for use in varying the tuning positions of the tuner so that no tools separate from the tuner elements themselves are required.

Other objects and features of my invention will be apparent from the following description taken with the drawing, in which:

Fig. 1 is a fragmentary side elevation partly in section, of one complete tuner unit of my invention taken along the line 1—1 of Fig. 3. The unit is shown in normal idle position.

Fig. 2 is a similar view of such unit in operated position and taken along the line 2—2 of Fig. 3.

Fig. 3 is a fragmentary top plan view of the tuner structure of my invention.

Fig. 4 is a detail view of the blank for the slide carriage in the apparatus of Figs. 1 to 3.

Fig. 5 is a side elevation similar to Figs. 1 and 2 of a modified embodiment of my invention.

In practicing my invention, I provide a manually operated automatic tuner for a radio receiver including a rotary shaft for connection with a variable condenser, or other resonance frequency changing means, having a plurality of control elements frictionally retained on such shaft. Each control element includes a mounting portion supported on the shaft and having friction means therefor so that each control element may be angularly adjusted upon the shaft independent of the other control elements. Each control element is moved to a predetermined tuning position by means of a selector or push-button unit which includes a linearly supported slideable carriage having a portion for engagement with a corresponding control element, and a push-button member supported on such carriage for engagement by the operator for linear movement of the carriage. The push-button member includes an elongated shank slidably supported upon the carriage with spring means intermediate the shank and such carriage to provide a yielding connection therebetween, and to normally maintain the push-button member in a retracted position with reference to the carriage. A socket portion is provided at the end of the shank for selected engagement with the friction means on the control element to adjust the friction means, and in turn prevent or permit the angular adjustment of the control element with reference to the rotary shaft. The push-button member is rotatably movable as well as linearly movable upon the carriage to accomplish the adjustment of the friction means.

Although my invention may take numerous forms only two have been chosen for illustration. Referring to the embodiment in Figs. 1 to 4, the tuner of my invention includes a frame 10 having a rotary shaft 11 journaled therein. The rotary shaft is coupled or otherwise connected to a variable condenser 12 or to any other desired resonance frequency changing means, such as a variable inductance. A plurality of control units are frictionally retained in adjacent relationship upon the rotary shaft 11, and each control unit comprises a cam 13 with a collar or bushing 14 integral therewith or rigidly secured thereto, and a set screw 16 threadably secured in the bushing 14. The head 17 of the set screw 16 is somewhat conical in shape and provided with a friction surface for ready connection with an adjusting tool as will be herein-after explained.

Each control unit is rotated to in turn rotate the shaft, or it is rotated with reference to the shaft, by means of a selector unit 18 comprising a carriage 19 having an elongated body portion with a guide portion 21 at one end, and a combination guide portion and push-button support at the other end indicated by the reference character 22. The slideable carriage is supported at the front and rear as shown in Figs. 1 to 3, by means of a pair of frame portions 23 and 24. A roller 26 is supported on the portion 22 of the carriage for engagement with the edge of the cam 13, and the carriage as a whole is supported in frame portions 23 and 24 in a position such that the roller moves on a straight line in alignment with the axis of the shaft 11. The body portion of the carriage 19 is offset so as to clear the shaft 11 and the bushings 14 thereon as is evident from Figs. 1 and 2.

In forming the carriage 19 for the selector unit 18 an ear 27 is knocked out of the portion 22 and a corresponding ear 28 is bent at right angles thereto at the outer end of such portion 22. A shank 29 for the push-button member for each selector unit is slidably supported in apertures in the ears 27 and 28 so as to move along a line in axial alignment with the axis of the roller 26 and consequently the axis of the shaft 11. A finger button 31 on one end of the shank 29 is positioned on the outside of a radio receiver cabinet for engagement by an operator, and a socket portion 33 is rigidly secured to the other end of the shank. The socket portion 33 has a cavity 34 therein for frictional engagement with the head 17 on the set screw of the corresponding control element and when the push-button member with the shank 29 is in the position illustrated in Fig. 2, the socket 33 is in operative engagement with the head 17 of the corresponding set screw. Although the roller 26 may be moved to the position shown in Fig. 2, the socket portion 33 is normally out of engagement with the head 17 by virtue of the pressure of the spring 36 supported on the shank 29 intermediate a washer 37 secured to the shank and the ear 27 on the carriage. The pressure of the spring 36 is such as to hold the shank 29 and button 31 thereon in a retracted position with reference to the carriage in the selector unit, such as shown in Fig. 1, although the carriage is moved to the position in Fig. 2 with the control element in a predetermined tuning position. As the operator continues to press on the button 31 against this spring pressure, the shank is moved linearly toward the set screw 16 until the cavity 34 is in engagement with the head 17 of the set screw. By rotating the button 31 to the right or to the left, the set screw is rotated in a similar direction for threadable adjustment to a position in frictional engagement with the shaft 11 or to a position out of frictional engagement with the shaft 11. When the operator releases his finger from the button 31, the spring 36 intermediate each carriage and the frame 10, as at the frame portion 23, pulls the entire selector unit to an idle position such as shown in Fig. 1.

The operation of the selector unit to rotate a corresponding control element and thereby rotate the shaft 11 therewith to a predetermined tuning position for the condenser 12 is apparent from the description above. In setting a cam 13 to an original predetermined position or resetting it to a subsequent predetermined position, the set screw 16 is loosened in the manner described above. When the socket portion 33 is in opera-

tive connection with the head 17 of the set screw, the roller 26 is in set position with reference to the cam 13 as shown in Fig. 2. With the roller 26 retained in set position, the shaft 11 is rotated manually by any desired means (not shown) thereby moving the rotors of the variable condenser 12 to a desired tuning position. This position can be indicated by a dial and pointer in the usual manner. With the set screw 16 out of frictional engagement with the shaft 11, and the cam 13 held by the roller 26 on the selector unit, the shaft 11 rotates with reference to the cam 13. At the predetermined tuning position of the condenser 12, the socket 33 is brought into operative engagement with the head 17 of the set screw, or possibly it might be in such engagement, and is rotated to threadably adjust the set screw 16 into frictional engagement with the shaft 11 thereby frictionally locking the cam 13 on the shaft so that subsequent rotation of the cam 13 by its corresponding selector unit 18 will bring the cam and hence the shaft 11 to a predetermined angular position for tuning.

In order to retain the carriage 19 of the selector unit 18 in operated position, with the roller 26 in the set-position cavity of the cam 13 as shown in Fig. 2, a latch 41 is pivotally mounted in the frame 10 for the tuner. A spring 42 secured to the latch maintains a constant lateral pressure on the latch so as to hold it against the top edge of the selector carriage. When the carriage is in the position shown in Fig. 2 the latch is pulled into latching engagement with the shoulder 43 provided in a notch adjacent the end of the guide portion 21 of the carriage so as to retain such carriage in operated position. The latch is effective both during tuning and during a setting operation so that the cam 13 of a control unit is retained in tuned position irrespective of whether pressure is maintained on the push-button 31. The push-button 31 may then be pushed inwardly at any time to effect an operative connection between the set screw 16 and socket portion 33 on the push-rod or shank 29. A beveled configuration transversely of the latch as shown in Figs. 1 and 2 causes the latch to be pivoted by an inwardly slideable selector unit to raise the latch and release any previously latched selector unit.

A modification of my invention is illustrated in Fig. 5. In this modification a control unit is provided with a control member or cam 13' having a split collar or bushing 14' either integral therewith or rigidly secured thereto. The split collar or bushing includes a pair of integral offset ears 46 and 47 extending radially from such bushing and the shaft 11. A set screw 16' with a somewhat conical corrugated head 17' is threadably secured in the two ears 46 and 47. The cam or control member 13' is rotated to, or held in a set position by means of a selector unit 48 including a linearly slideable carriage 49 supported in a pair of frame portions 51 and 52 in front of the control member. A roller 53 is rotatably mounted at the end of an extension on the carriage 49 and moves in alignment with the axial center of the shaft 11. The carriage 49 is moved linearly by a push-button 54 secured to one end of a push-rod or shank 56 slidably carried in a pair of ears 57 knocked out of the body portion of the carriage 49 in the forming of the same. The ears 57 are offset from a line through the axial center of the shaft 11 and carry the shank 56 in such offset position, but in alignment with the set screw 16' in the bushing 14' of the control member. A

cavity 58 in the end of the shank 56 is adapted for frictional engagement with the head 17' of the set screw when the shank 56 is pushed inwardly against the pressure of a spring 59 carried on the shank intermediate an ear 57 and a washer 61. The washer is rigidly secured on the shank 56, or at least locked against longitudinal movement thereon.

The operation of the modification is similar to that for the structure of Figs. 1 to 4, inclusive, described above, with the selector unit being slidable to rotate the cam 13' to a set position, and the push-button 54 being slidable inwardly thereafter for meshing engagement between the cavity 58 and the set screw head 17'. The push-button and connected shank member may then be rotated to adjust the screw 16' to friction or non-friction position.

From the above description, it is apparent that I provide a simplified, sturdy, manually operated tuner for a radio receiver in which the tuning operations may be accomplished with a linear inward movement of the actuator portion of the tuner. The control portion of such unit may be set or reset to predetermined tuning positions by means carried directly on the tuner and having an operative function therein. The setting or resetting operation may be accomplished entirely from the front of the tuner.

The disclosures of this application are illustrative and the invention is not to be limited by them. In fact, if modifications or improvements are not at once obvious, they may be devised in the course of time to make additional use of the broad ideas taught and covered by this application. The claims are intended to point out novel features and not to limit the invention except as may be required by prior art.

I claim:

1. Tuning apparatus for a radio receiver including a rotary shaft, a control unit on such shaft adapted to be adjusted relative to said shaft and having friction adjusting means thereon for securing said unit in an adjusted position, means for moving said control unit to predetermined tuning positions for said apparatus, means selectively connectible with said friction adjusting means to adjust the same to release said control unit from, or secure it to said shaft, and means on said means for moving said control unit slidably supporting said selectively connectible means thereon for linear movement into and out of operative connection with said friction adjusting means.

2. Control apparatus for a radio receiver including a rotary shaft, a control unit supported on said shaft having threaded friction adjusting means thereon for varying the friction between such control unit and shaft to permit or prevent the movement of such control unit relative to said shaft, a selector unit for moving said control unit including a sliding carriage, means for supporting said carriage for linear slidable movement with reference to said control unit, said selector unit including a portion selectively movable with reference to said carriage and operatively connected therewith to move said carriage to tuning position and selectively engage said friction adjusting means on said control unit for adjusting such means.

3. A tuner for a radio receiver including a frame, a control shaft journaled in said frame, control means on said shaft including a control portion and a mounting portion, adjustable means in said mounting portion for frictional

engagement with said shaft to permit or prevent movement of said control means with reference to said shaft, a selector carriage slidably mounted in said frame, an actuator, means for slidably mounting said actuator on said selector carriage, means operatively connecting said carriage and actuator in a manner so that the carriage is moved by movement of said actuator and yet said actuator is movable independently of the carriage for operative connection with said adjustable means, and with said actuator having a portion operatively connectible with said adjustable means.

4. Control apparatus for a radio receiver including a rotatable shaft, control means on said shaft including a control portion and a radially split bushing thereon, adjustable means in said bushing at the split portion for varying the frictional pressure thereof on said control shaft, movable selector unit comprising a carriage having an extension in alignment with the axial center of said control means for engagement with said control means, means on said carriage for supporting an actuating member thereon, an actuating member carried on said supporting means, said actuating member being off-center with respect to said control portion but in alignment with said adjustable means, and said actuating member having an adjusting portion on one end thereof for selected operative connection with said adjustable means to adjust the same and vary the frictional pressure intermediate said control means and the rotatable shaft.

5. A control device for controllable apparatus including a rotary shaft, a control unit mounted on said shaft having means thereon for adjusting the friction between said control unit and said shaft, a selector unit for rotating said control unit including a slidable carriage, and a push member rotatably mounted on said carriage for moving said carriage into engagement with said control unit upon movement of said push member, with said push member adapted to be moved relative to said carriage for operative connection with said friction adjusting means to rotate said friction adjusting means to change the adjustment thereof.

6. A control device for controllable apparatus including a rotary shaft, a control unit mounted on said shaft comprising a control portion and a bushing portion thereon rigid with respect to such control portion, a set screw threadably secured in said bushing portion for frictional engagement with said shaft, a selector unit for rotating said control unit including a slidable carriage having an engaging portion in alignment with the axial center of said control unit for engaging said control portion, means for supporting said carriage for linear slidable movement, and a push member rotatably mounted on said carriage in alignment with the axial center of said control unit for moving said carriage into engagement with said control unit upon movement of said push member, with said push member adapted for operative connection with said set screw to rotate the same to vary the frictional adjustment between the set screw and the rotary shaft.

7. A control device for controllable apparatus including a rotary shaft, a control unit mounted on said shaft comprising a control portion and a split mounting portion thereon rigid with respect to such control portion, threaded adjusting means in said split mounting portion for varying the frictional pressure intermediate said

mounting portion and the rotary shaft, a selector unit for rotating said control unit including a slideable carriage having an engaging portion in alignment with the axial center of said control unit for engaging said control portion, means for supporting said carriage for linear slideable movement, and a push member rotatably mounted on said carriage in a position offset from a line through the axial center of said control unit but in alignment with the adjusting means in said split mounting portion for moving said carriage into engagement with said control unit upon movement of said push member, with said push member adapted for operative connection with said adjusting means to rotate the same to vary the frictional pressure between the control unit mounting portion and the rotary shaft.

8. A tuner for a radio receiver including a rotary shaft, a control unit on such shaft having friction adjusting means thereon for varying the frictional engagement between such control unit and shaft, a selector unit for moving said control unit to a predetermined tuning position, said selector unit including a control unit driving portion and an actuator slideably mounted on said driving portion, and spring means for controlling the relative movement between said actuator and said control unit driving portion, said actuator having an adjusting portion at one end thereof, and said actuator being operable to move said driving portion into contact with said control unit and being operable to engage said adjusting portion with said friction adjusting means for changing the adjustment thereof.

9. A tuner for a radio receiver including a frame, a rotary control shaft mounted in said frame, a control unit supported on said shaft having friction adjusting means for varying the friction between such control unit and shaft to permit or prevent the movement of such control unit relative to said shaft, a selector carriage slideably mounted in said frame to contact and move said control unit to a predetermined tuning position, a push member rotatably supported on said carriage and slideably movable relative thereto, and spring means for control-

ling the relative linear movement between said push member and selector carriage, initial linear movement of said push member acting to urge said selector carriage into contact with said control unit and later linear movement of said push member acting to engage said push rod with said friction adjusting means, said push member being adapted for operative connection with said friction adjusting means to rotate the same to change the adjustment thereof.

10. In radio tuning mechanism having frame means, tuning control means including a carriage slideably supported in said frame means, a combination actuating and friction changing unit supported on said carriage for slideable relative movement, an adjustable control element spaced from said combination unit, axis means supporting the control element and friction locking means operatively connected therewith, with said combination unit having a push button on one end thereof and having a portion at the other end selectively engageable with a portion of the friction locking means, and with said combination unit being movable when in engagement with the portion of the friction locking means for moving the friction locking means to locking or unlocked position.

11. In radio tuning mechanism having frame means and control axis means, the means for rotating said control axis means to a predetermined control position including a carriage slideably supported in said frame means, a push unit supported on said carriage for slideable relative movement, a control element supported for adjustment relative to the control axis means, friction locking means operatively connected with said control element to lock said element in an adjusted position and having a head portion thereon, said push unit having an actuating portion at one end and having a portion at the other end engageable with the outside of said friction locking means head portion, with said friction locking means being rotatable by said push unit in the engaged position to control element locking position.

ALEXANDER W. PLENSLER.
